UNITED STATES PATENT OFFICE

106,850

DESIGN FOR A DRESS

Sidney J. Poster, New York, N. Y.

Application October 8, 1937, Serial No. 72,057

Term of patent 3½ years

To all whom it may concern:

Be it known that I, Sidney J. Poster, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The floral bandings on the sleeves and waist portion of the dress represent embroidery.

I claim:

The ornamental design for a dress, substantially as shown and described.

SIDNEY J. POSTER.
